UNITED STATES PATENT OFFICE.

LUCIUS HAMLIN, OF SEBAGO LAKE, MAINE.

FIRE-ESCAPE LADDER.

SPECIFICATION forming part of Letters Patent No. 275,905, dated April 17, 1883.

Application filed December 22, 1882. (No model.)

To all whom it may concern:

Be it known that I, LUCIUS HAMLIN, a citizen of the United States, residing at Sebago Lake, in the county of Cumberland and State of Maine, have invented a new and useful Fire-Escape Extension-Ladder, of which the following is a specification, reference being had to the accompanying drawings.

This invention relates to an improved extension-ladder that is designed to also serve as a fire-escape; and it has for its object to provide a simple, durable, inexpensive and efficient device that will operate independent of the building, and will not necessarily be supported against the same or have any other connection therewith.

The invention consists substantially in an extensible frame mounted on a suitable portable or stationary platform and carrying a flexible ladder. The frame is provided with mechanism by which it may be quickly and conveniently extended, so as to support the flexible ladder when the device is in use.

In the drawings, Figure 1 is a perspective view of my improved fire-escape ladder in position for transportation. Fig. 2 is a like view of the same extended for use. Fig. 3 is a vertical longitudinal sectional view of the device when contracted. Fig. 4 is a vertical transverse sectional view of the device in like position. Fig. 5 is a detail top view of the extensible frame. Fig. 6 is a horizontal sectional detail view taken through the extensible frame on the line $z z$, Fig. 4.

Referring to the drawings, A designates a platform for supporting the extension-ladder mechanism. This platform may be of any suitable construction, but is preferably constructed as shown in the annexed drawings, and comprises longitudinal beams B B, united at their ends by cross-beams C C, and mounted upon wheels D, whereby the apparatus can be transported from building to building, as may be required.

E designates the extensible ladder-supporting frame, which comprises several telescoping sections, F, F^2 , and F^3 . The side pieces $f f$ of the lower section, F, are pivoted near their lower ends to the beams B B of the supporting-platform, and are united at their tops by parallel cross-pieces G G, between which

the side pieces $f^2 f^2$ of the next section, F^2 , slide. The side pieces $f^2 f^2$ are connected at their lower ends by parallel cross-pieces H H, that extend and embrace the side pieces $f f$, and are also connected at their tops by parallel cross-pieces I I. The side pieces $f^3 f^3$ of the top section, F^3 , are connected by extended bottom cross-pieces, J J, and top cross-piece, K.

The means for extending the frame E comprises the following mechanism: A drum, L, is fixed on a shaft, M, arranged transversely to the said frame E, and journaled in bearings N N in cross-pieces O O, that are supported on the beams B B. This drum-shaft M is provided with a crank, P, by which it may be operated, and to the drum are secured ropes or cables Q Q, that extend from the drum in opposite directions. Each rope Q passes under bearings R at the lower portion of the side pieces $f f$, from which it extends up over bearings S at the top of said side pieces, under bearings T at the bottom of the side pieces $f^2 f^2$, up over bearings U at the top of the latter side pieces, and is secured to the lower ends of the side pieces $f^3 f^3$ of the top section, F^3 . By turning the crank P the ropes Q Q are caused to wind on the drum L to extend the frame E. The extensible frame may of course be provided with any desired number of telescoping sections, as described.

The beams B B are provided with a lateral extension, V, in rear of the pivot W of the side pieces $f f$, against which extensions the lower ends of the latter abut to limit forward swing of the frame E on the pivots W W. To the beams B B, in rear of these extensions V, is pivoted an arm, X, that may be thrown forward to a horizontal position, when it will rest on the extension V and abut against the side pieces $f f$, to prevent rearward swing of the frame E. Thus by means of the extensions V, which prevent forward swing of the frame E, and the arms X, which prevent rearward swing, the frame E can be locked in vertical position when desired.

At the front end of the platform A a drum, A⁵, is fixed on a transverse shaft, B⁵, having an operating-crank, C⁵, and to this drum are secured the ends of the bottom of a flexible ladder, D⁵, that is arranged to wind on the said drum, and has its ends at the top secured

to the cross-piece K. Therefore, as the frame, E is extended the ladder unwinds from the drum and is carried up by the extensible frame which then supports it while in use. After 5 use the extensible frame may be drawn down by winding up the ladder on its drum, and when all the sections of the said frame have telescoped it is laid over to a horizontal position, as shown in Fig. 1 of the drawings, so 10 that it can be conveniently transported, and will pass under the door of the engine-house or other building, where it may be stored.

The herein-described flexible ladder may be 15 constructed of rope or any other suitable material, and to render it fire-proof it may be formed of wire or other metallic strands. For the same reason the extensible frame may be formed of metallic tubing.

E⁵ E⁵ designate horizontal swinging arms, 20 that are pivoted one on each side to the beams B B, and are provided at their outer ends with downwardly-extending stakes F⁵. The function of these laterally-swinging arms is to obviate any liability of the device falling over 25 laterally after it is extended and in position.

The operation and advantages of my invention are obvious.

The device is very simple and convenient, and when desired need only be far enough ex- 30 tended to reach to a lower story of the build- ing.

I am aware that portable frames carrying extensible frames to which are secured flexible ladders and operated by a drum at the bottom are old, and such I do not claim broadly as of my invention.

35

I claim as my invention—

1. In an extension-ladder, the combination of a base or platform having lateral extensions, an extensible frame hinged or pivoted thereto in front of the said extensions, so as to 40 swing rearwardly, a drum journaled and arranged transversely in front of the frame, and a flexible ladder arranged to wind on this drum and having its top ends secured to the top of the extensible frame, as set forth.

45

2. In an extension-ladder, the combination of a base or platform having lateral extensions, and arms pivoted in rear of these extensions, an extensible frame hinged to the platform in front of the latter, and adapted to be retained 50 in position by the said arms and extensions, and a flexible ladder arranged in front of the said frame and secured thereto, as set forth.

In testimony that I claim the foregoing as my own I have hereto affixed my signature in 55 presence of two witnesses.

LUCIUS HAMLIN.
